TOY BUILDING PANELS

Charles S. Ogsbury, Gold Hill, and Don C. Witte,
Boulder, Colo.

Filed July 22, 1969, Ser. No. 18,309

Term of patent 14 years

Int. Cl. D21—01

U.S. Cl. D34—15

FIG. 1 is a perspective view of one form of toy building panel showing our new design.

FIG. 2 is a front view of the form which is shown in FIG. 1.

FIG. 3 is a sectional view taken along lines 3—3 of FIG. 2.

FIG. 4 is a side elevational view of the form shown in FIG. 1.

FIG. 5 is a perspective view of a modified form of toy building panel showing our new design.

FIG. 6 is a front view thereof.

FIG. 7 is a right side elevational view of the form shown in FIG. 5 with the top plan view thereof being of a similar appearance.

FIG. 8 is a bottom plan view of the form shown in FIG. 5; and

FIG. 9 is a left side elevational view of the form shown in FIG. 5.

We claim:

The ornamental design for toy building panels, as shown and described.
